UNITED STATES PATENT OFFICE.

FRANK McDONOUGH, OF EAU CLAIRE, WISCONSIN.

FEED MECHANISM FOR BAND-SAW RESAWING-MACHINES.

SPECIFICATION forming part of Letters Patent No. 589,014, dated August 31, 1897.

Application filed October 3, 1896. Serial No. 607,797. (No model.)

To all whom it may concern:

Be it known that I, FRANK McDONOUGH, a citizen of the United States, residing at Eau Claire, in the county of Eau Claire and State 5 of Wisconsin, have invented a new and useful Feed Mechanism for Band-Saw Resawing-Machines, of which the following is a specification.

This invention relates to band resawing machines, and more particularly to the feed-works for delivering the sawed lumber to the saw for resawing; and it has for its object to provide certain improvements in feed-works of this character whereby the same can be 15 designed for use in connection with any style of band-mill and which shall possess every adjustment necessary for the accurate feeding of the material to the saw.

With these and many other objects in view, 20 which will readily appear as the nature of the invention is better understood, the same consists in the novel construction, combination, and arrangement of parts hereinafter more fully described, illustrated, and claimed.

25 In the drawings, Figure 1 is a top plan view of the band-resaw feed-works constructed in accordance with this invention. Fig. 2 is a side elevation thereof, partly in section. Fig. 3 is an end view, partly in section, of the feed-works. Fig. 4 is a plan view of the roll-adjusting mechanism employed in connection with the set of feed-rolls next to the saw. Fig. 5 is a similar view of the roll-adjusting mechanism employed in connection with the 35 first set of feed-rolls farthest from the saw. Fig. 6 is an enlarged plan view of the equalizing-lever connections with the pair of adjusting screw-rods for each pair of slide-tables. Fig. 7 is an enlarged detail sectional view of the adjustable bearing-box support for the upper ends of the first set of feed-rolls. Fig. 8 is a similar view on the line 8-8 of Fig. 2. Fig. 9 is an enlarged detail sectional view of the pivotal bearing-support for the lower ends of the intermediate feed-rolls. 45

Referring to the accompanying drawings, the numeral 1 designates the base of an ordinary band-saw mill and having the usual stand 2 for carrying the lower guide 3 for the 50 band-saw 4, such construction being common in connection with ordinary band-saw mills

and is illustrated for the purpose of showing the relation of the feed-works to the saw 4.

The entire feed-works for use in connection with the saw 4 are supported by a base-frame 5, which is bolted to the foundation of the mill far enough back from the saw to permit of the adjustment of the feed-works, so that the saw may be readily taken off and put on, as will be hereinafter more particularly referred to. The base-frame 5 is provided at opposite upper sides with the longitudinally-disposed dovetailed slideways 6, which are slidably engaged by the opposite parallel dovetailed slide-feet 7, projected from 65 the under side of the movable feed-carriage 8 and forming a part of such carriage. The feed-carriage 8 is movable longitudinally of the base-frame 5 toward and away from the band-saw 4, and has fitted to its under side 70 at a suitable point the fixed feed-nut 9, which is engaged by the carriage-adjusting screw 10, swiveled near its outer end, as at 11, in a transverse bearing-bar 12 at one end of the base-frame 5, and having fitted on its extremity at the outer side of the bearing-bar 12 the jam-nuts 13 for securing the screw stationary after the proper adjustment of the carriage toward or away from the saw, it being noted that the set-screw 10 is turned in 75 any suitable manner at its outer end to provide for the sliding movement of the carriage 8 when necessary, as will be more fully explained.

The slideable feed-carriage 8 essentially 85 comprises the parallel slide-feet 7 and a pair of transverse semitubular table-supports 14, spaced a distance apart and of a greater length than the width of the base-frame 5, on which the carriage slides. The transverse semi-tubular table-supports 14 form casings or 90 housings for certain parts of the feed-works, to be hereinafter referred to, and are provided at their opposite upper side edges with the longitudinally-disposed guide-flanges 15, that 95 are slidably engaged by the inturned slide-flanges 16 at opposite side edges of the slide-tables 17 17^a, mounted to slide on top of the supports 14 and forming top plates therefor. Interposed in the spaces between the interlocked flanges 15 and 16 are suitable wear-plates 15^a, properly adjusted to a working fit 100

by means of the set-screws 16^a, mounted in the flanges 16, it being obvious that the wear-plates 15^a and the set-screw adjustments therefor provide ready means for taking up any looseness that may occur from the wear of the parts. A pair of the slide-tables is mounted on each of the transverse table-supports 14 and are designed to carry a set of feed-rolls for assisting in accurately feeding the timber to the saw 4 for the purpose of being resawed. In the present invention each of the pair of slide-tables 17, mounted to slide in opposite directions on the transverse table-support 14 farthest from the saw, supports thereon an upright roll-bracket 18, provided at its upper end with a horizontally-disposed squared guide-yoke 19, at the outer side of which yoke the bracket is formed with a hollow offstanding boss 20, provided therein with a threaded opening 21 to adjustably receive an exteriorly-threaded adjusting-sleeve 22, provided at its outer end with a squared head 23 and loosely receiving therein an adjusting-bolt 24. The adjusting-bolt 24 is provided intermediate of its ends with a collar 25, arranged within the boss 20 at the inner end of the sleeve 22, and at its outer end the said bolt 24 carries a nut 26, disposed at the outer end of the sleeve 22 and providing for properly holding the sleeve on the bolt, so that by a turning of the former the latter will be moved in a longitudinal direction inward or outward to provide for the sliding adjustment of the squared sliding bearing-box 27, loosely fitting in the squared guide-yoke 19 and having the inner extremity 28 of the bolt 24 threaded therein.

The upright roll-brackets 18, carried by the oppositely-located and oppositely-movable slide-tables 17 on the front table-support 14, are each equipped at their upper ends with the bearing-boxes 27, adjustable in the manner referred to, and said bearing-boxes are provided therein with the vertical bearing-openings 29, which receive the upper spindle extremities 30 of the upright feed-rolls 31, the lower spindle extremities 32 of which rolls are journaled in the pivotal bearing-collars 33, arranged at the lower ends of the rolls 31, and pivotally supported between oppositely-located stud-pins 34, mounted in lugs 35, projected upwardly from the tables 17 at opposite sides of the collars 33, and immediately below the pivotal bearing-collars 33 for the lower spindle ends of the rolls 31 the lower spindle ends of the rolls 31 have keyed thereon the horizontally-disposed beveled gear-wheels 36.

The horizontally-disposed beveled gear-wheels 36 are disposed below the plane of the tables 17, carrying the brackets 18, and within the tubular table-support 14, supporting the said tables, and said gear-wheels 36 mesh with vertically-disposed adjacent beveled gear-wheels 37, provided with elongated bearing-hubs 38, mounted for rotation in bearing-boxes 39, disposed within the table-support

14 and bolted or otherwise suitably secured to the under side of the tables 17, carrying the brackets 18. The beveled gear-wheels 37 and their hubs 38 are feathered on the single drive-shaft 40, extending longitudinally throughout the entire length of the table-support 14 farthest from the saw and journaled in the inwardly-disposed journal-boxes 41, formed at opposite ends of the said table-support. The said drive-shaft 40 projects beyond the ends of the table-support 14, in which it works, and has fitted on such projecting end the sprocket-wheels 42, which are employed to communicate motion to the other parts of the works, to be presently referred to, and on one of the projecting ends of the shaft 40 is fitted an extra sprocket-wheel 43, which acts in the capacity of a drive-sprocket and receives a chain from the power used for operating the feed-works, it being noted at this point that the rotation of the shaft 40 provides for the simultaneous rotation of both of the feed-rolls 31, between which the timber 90 is fed toward the saw, said feed-rolls being also movable toward and away from each other by reason of being mounted within the brackets 18, carried by the pair of front slide-tables, or those farthest from the saw toward 95 which the material is fed.

The slide-tables 17^a, mounted on the rear table-support 14 next to the saw, carry the upright roll-brackets 44, which are curved inwardly toward the longitudinal center or saw 100 line of the feed-works, and are provided at their upper ends with suitable bearing-boxes 45, in which are journaled the upper spindle extremities 46 of the rear feed-rolls 47, disposed in vertical parallel planes and having 105 their lower spindle extremities 48 mounted in suitable bearing-boxes 49, fitted on the slide-tables 17^a, below the bearing-boxes 45 at the upper ends of the brackets 44. Below the lower bearing-boxes 49 the lower spindle 110 extremities 48 of the rear feed-rolls 47 have keyed thereon the horizontal beveled gear-wheels 50, meshing with adjacent vertically-disposed beveled gear-wheels 51, slidably mounted on the inner ends of the opposite 115 longitudinally-aligned shaft-sections 52, and provided at one side with hub extensions 53, loosely turning in the bearing-boxes 54, disposed within the rear table-support 14 and bolted or otherwise suitably secured to the 120 under sides of the tables 17^a, such arrangement of parts being substantially similar to the corresponding parts within the rear table-support 14, supporting the tables 17, excepting that in connection with the rear 125 pair of parallel oppositely-movable feed-rolls 47 is employed separate shaft-sections 52 to permit the saw 4 to project into the saw-space 53^a, formed in the front side of the rear table-support 14 and the adjacent ends 130 of the slide-tables 17^a. It will be seen that by reason of this construction the feed-works carried by the carriage 8 can be adjusted close up to the saw, so that the cutting edge

of the latter will be disposed close to the center of the rear set or pair of rolls 47. The opposite aligned shaft-sections 52 are journaled near their outer ends in the bearing-collars 54^a, formed at the ends of the rear table-support 14, and the outer ends of said shaft-sections 52 have mounted thereon the sprocket-wheels 55, adapted to be engaged by ordinary sprocket-chains running from the sprocket-wheels 42 of the shaft 40, whereby said latter shaft will provide means for simultaneously rotating the rear shaft-sections 52 and the front feed-rolls 47, geared therewith. The sprocket-chains (shown in dotted lines in Fig. 1) which connect the aligned wheels 42 and 55 at each side of the feed-carriage are maintained at the proper tension by means of the idler or tightener sprocket-wheels 56, arranged at opposite sides of the carriage 8 between the wheels 42 and 55, and the said sprocket-wheels 56 are mounted on the journal-bolts 57, the inner ends of which are adjustably secured in the vertically-disposed slots 58, formed centrally in the wheel-brackets 59, arranged between the table-supports 14, near the ends thereof, and bolted or otherwise suitably fastened thereto, as at 60, it being obvious that the vertical adjustment of the wheels 56 will provide for the proper tightening of the sprocket-chains connecting the oppositely-located pairs of wheels 42 and 55.

The upright roll-brackets 44, carrying the rear upright feed-rolls are provided at their upper ends with the laterally-extending arms 61, provided with the horizontally-disposed squared guide-yokes 62, corresponding to the yokes 19 of the brackets 18 and having adjustably mounted therein the squared sliding bearing-boxes 63. The squared sliding bearing-boxes 63 are adjusted within the yokes 62 by adjusting devices 64, identical in construction to the bolt-adjusting devices described in connection with the bearing-boxes 27 for the upper ends of the rolls 31, and the said bearing-boxes 63 have journaled therein the upper spindle extremities 65 of the small upright intermediate feed-rolls 66, which are of a smaller diameter than the front and rear rolls 31 and 47, but are arranged in alignment with the said rolls, respectively, at opposite sides of the longitudinal center or saw-line of the works. The upright intermediate feed-rolls 66 have their lower spindle extremities 67 journaled in the pivotal bearing-collars 68, pivotally supported between oppositely-located stud-pins 69, mounted in opposite sides of the bearing-brackets 70, bolted or otherwise suitably secured to the slide-tables 17^a at one side of the upright brackets 44, carrying the rolls 47.

The upper spindle extremities 65 of the rolls 66 have mounted thereon the pinions 71, meshing with intermediate spur-gears 72, journaled on the bearing-studs 73, projected from the upper sides of the lateral arms 61 of the brackets 44, and said spur-gears 72 in turn

mesh with the gear-wheels 74, mounted on the upper spindle extremities 46 of the rear feed-rolls 47, whereby said latter rolls will provide means for communicating motion to the intermediate rolls 66 between the said front and rear sets or pairs of feed-rolls, as will be readily apparent.

From the foregoing description it will be seen that the rear pair of oppositely-movable slide-tables 17^a carry the rear and intermediate pairs of feed-rolls 47 and 66, while the front pair of oppositely-movable slide-tables 17 carry the front pair of feed-rolls, but all of which feed-rolls are arranged in substantial alignment and respectively at opposite sides of the saw-line of the feed-works to provide for accurately feeding the material up to the saw. In connection with each pair of oppositely-movable slide-tables supported on the table-supports 14 is employed a pair of adjusting screw-rods 75, which screw-rods are of different lengths and extend within the semitubular table-supports under the slide-tables. The adjusting screw-rods 75 for each pair of the slide-tables extend beyond one end of the support for such tables and are provided with inner threaded ends 76, engaging in the feed-nuts 77, bolted or otherwise suitably secured, as at 78, respectively, to the under side of the separate slide-tables of the pair of such tables under which the adjusting screw-rods are arranged.

The arrangement of the feed-nuts 77, whereby each of the slide-tables will carry one of such nuts, provides for the adjustable connection of one of the screw-rods 75 with one of the slide-tables of a pair of such tables, and the adjustable connection of the other screw-rod with the other table of the same pair, so that the simultaneous adjustment of the screw-rods will provide for the simultaneous adjustment of the two slide-tables.

The outer ends of each pair of adjusting screw-rods 75 loosely receive thereon the knuckle-blocks 79, which are pivotally embraced by the forked ends 80 of a horizontal oscillatory adjusting-lever 81, arranged between the outer ends of the rods 75 and mounted on the upper extremity of a vertical rock-shaft 82, journaled in an elongated vertical bearing-hub 83, formed at the outer side of a supporting-bracket 84, bolted to one side of the carriage 8, or to the semitubular table-support 14, into which the rods 75 extend. On the lower end of the vertical rock-shaft 82 is fitted the collar end 85 of a rock-arm 86, provided with a rounded tip 87 at its free terminal, which plays in the slotted end 88 of a bell-crank lever 89, pivotally mounted at its angle, as at 90, at one side of a pendent-arm extension 91 of the bracket 84. At its end opposite the slotted end 88 thereof the bell-crank lever 89 has bolted or otherwise suitably fastened thereto one end of a tension-lever 92, on the free end of which is adjustably mounted the tension-weight 93, which normally moves the slide-tables toward each

other to provide for holding the feed-rolls against the material being fed to the saw.

One of the rods 75 of each pair has mounted at one side of the knuckle-block 79 thereon 5 an adjusting hand-wheel 94, engaging with a threaded portion 95 of such rod, while the other rod 75 of the same pair is threaded at opposite sides of the knuckle-block 79 thereon, as at 95^a, and on which threaded portions 10 95^a are mounted for movement the adjusting hand-wheels 96, which provide for the adjustment of the knuckle-block 79 therebetween, and the consequent oscillation of the lever 81 and opposite longitudinal movement of the 15 two rods 75. In addition to the adjusting hand-wheels referred to, each pair of the adjusting-rods 75 have mounted thereon the intergeared equalizing gear-wheels 97, which also have a sliding engagement to admit of 20 the longitudinal movement of the rod 75 without becoming disengaged.

In connection with the three sets of feed-rolls, which are adjusted toward and away from each other and automatically pressed 25 against the material in the manner described, is employed a longitudinally-arranged rest-bar 98, secured on top of the carriage 8 in line with the longitudinal center or saw line of the feed-works between the oppositely-located and oppositely-movable slide-tables 17 and 17^a. The said longitudinally-arranged rest-bar 98 is disposed just below the plane 30 of the lower ends of the feed-rolls, so as to form a support for the lumber passing to the saw, and at its rear end the bar 98 is forked 35 or bifurcated, as at 99, to permit the band-saw to extend in between the rear pair of feed-rolls 47, said fork or bifurcation 99 thereby providing a rest for the lumber to a point beyond 40 the cutting-point, which insures a true and accurate sawing of the material.

The forked or bifurcated rear end of the bar 98, in conjunction with the reentrant saw-space 53^a, permits the saw to extend in between the rear pair of feed-rolls 47, and it is 45 therefore important to note the function of the intermediate feed-rolls 66. These intermediate feed-rolls 66 are necessary to insure the proper positive feed of the lumber between the rear rolls 47, as these latter rolls, while acting as feed-rolls, more properly serve 50 as guide-rolls for the lumber. The band-saw extends directly into the space between the said rear feed-rolls 47, and it is therefore obviously necessary to provide other means than 55 the rolls 47 for firmly supporting or holding the lumber adjacent to the point where the saw cuts the same. This is accomplished by the use of the rolls 66, which maintain a relatively close relation to the rear rolls 47, so as 60 to firmly brace and hold the lumber adjacent to the rolls 47, and also to positively feed the lumber forward between these rolls.

In the use of the feed-works it is important 65 to note that the works are designed for use in connection with any style of band-mill, allowing the band-saw to be placed on the

wheels in its proper position, and not to require, as in some band-resaws, that the saw be placed on the wheels back side foremost. 70 To accomplish this desired result, the carriage 8 moves the entire feed-works toward and away from the saw by means of the adjustment of the carriage-adjusting screw 10. By means of this screw the whole feed-works 75 may be moved back far enough to allow the band-saw to be taken off of the front side of the wheels, the base-frame 5 being located sufficiently far from the sawmill to allow the saw to come forward far enough to be taken 80 off of the wheels. This operation of the feed-works is also important, so as to dispose the cutting-point of the saw well up to the center of the rear feed-rolls, thereby avoiding any chance of the lumber being operated on 85 springing out of place and thereby causing bad work.

In the operation of the feed-works it is sometimes necessary to plumb or adjust the feed-rolls 31 and 66, and whenever this is necessary the bearing-boxes for the upper ends 90 of such feed-rolls are adjusted inward or outward, thereby allowing said rolls to swing on the pivotal supports for their lower ends and assume the desired inclination, so as to press 95 evenly against timber of uneven thickness, so as to insure a constant pressure of the feed-rolls across the whole face of the material while passing to the saw. In addition to the individual adjustment of the rolls 31 and 66 all of the feed-rolls are caused to preserve a constant pressure on the material by means of the weighted lever connections with the outer ends of the adjusting screw-rods 75, it being obvious that the weights 93 cause such a movement of the lever connections therewith as to provide for moving the rods 75 in a direction to constantly draw the feed-rolls against the work being fed to the saw, and at this point it is to be noted that the equalizing-gears 97, which gear the rods 75 of each pair together, are important to keep the rolls at an equal distance from the saw-line of the machine. While the equalizing-gears 97 allow the pressure mechanism to move the rods 71 in a longitudinal direction, it will be understood that in first adjusting the rolls the adjusting-rods may be turned in any suitable manner to operate in the nuts 77, and the gears 97 will cause a uniform or equal movement of the screw-rods, so that when the rolls are once set the proper distance from the saw to split a certain thickness of lumber through the center said rolls will always maintain an equal distance from the saw without further adjustment, irrespective of the opening and closing of the rolls for any other thickness of timber.

The adjusting hand-wheels at the outer ends of the screw-rods 75 are of importance to provide for adjusting the feed-rolls the proper distance from the saw-line when the machine is in operation and if from any cause the saw is not working in the exact center of

the board. Under these conditions the operator can readily manipulate the adjusting hand-wheels so as to oscillate the levers 81 sufficiently to correct the uneven feeding, so 5 it will therefore be seen that by means of the adjusting hand-wheels the feed-works while in operation are under perfect control so far as gaging the exact thickness of stock being sawed.

10 From the foregoing it is thought that the construction, operation, and many advantages of the herein-described feed-works will be readily apparent without further description, and it will be further understood that 15 various changes in the form, proportion, and the minor details of construction may be resorted to without departing from the principle or sacrificing any of the advantages of this invention.

20 Having thus described the invention, what is claimed, and desired to be secured by Letters Patent, is—

1. In a band-resaw feed-works, a stationary base-frame, and a feed-carriage slidably 25 mounted on the base-frame and carrying a series of feed-rolls arranged respectively at opposite sides of the saw-line, said feed-carriage having a timber-rest, and a saw-receiving bifurcation formed at the side thereof 30 next to the saw and extending into the timber-rest between the rear pair of feed-rolls, substantially as set forth.

2. In a band-resaw feed-works a stationary base-frame provided at opposite upper sides 35 with longitudinally-disposed slideways, a slidable feed-carriage supported on the base-frame and essentially comprising a pair of transverse front and rear semitubular table-supports, intermediate connections between 40 said supports, and parallel slide-feet connecting the two supports at their lower sides and engaging in the slideways of the base-frame, slide-tables mounted on each table-support and carrying rotary upright feed-rolls, and 45 suitable operating mechanism having gear connection with the lower spindle extremities of the feed-rolls within the semitubular table-supports, substantially as set forth.

3. In a band-resaw feed-works, a stationary base-frame, a feed-carriage slidably mounted on the base-frame and having a pair of transverse front and rear semitubular table-supports, a pair of slide-tables mounted on each of the table-supports over their open sides and 55 carrying rotary upright feed-rolls, shafts arranged in the semitubular table-supports and geared with each other and with the feed-rolls to provide for the simultaneous rotation of the latter, pressure-adjusting mechanism 60 for the tables of each pair, and an adjusting device for the feed-carriage, substantially as set forth.

4. In a band-resaw feed-works, a stationary base-frame, an adjustable feed-carriage 65 mounted on the base-frame and provided with a pair of transverse front and rear semitubular table-supports provided at their op-

posite upper side edges with longitudinally-disposed guide-flanges, a pair of slide-tables mounted on each of said table-supports and 70 carrying rotary upright feed-rolls, said slide-tables being provided at opposite side edges with inturned flanges interlocking with those of the table-supports, and suitable adjusting mechanism for each pair of slide-tables, substantially as set forth. 75

5. In a band-resaw feed-works, a stationary base-frame, a feed-carriage adjustably mounted on the base-frame and having at its side next to the saw a reentrant saw-space, 80 front and rear pairs of upright feed-rolls adjustably supported on the carriage respectively at opposite sides of the saw-line, the rolls of the front and rear pairs being of a uniform diameter, and the rear pair of rolls 85 being arranged respectively at opposite sides of said saw-space, a pair of intermediate feed-rolls arranged between and in line with the other pairs of rolls and in a relatively close relation to the rear pair of rolls, and suitable 90 pressure-adjusting mechanism for simultaneously and uniformly adjusting the rolls at opposite sides of the saw-line, substantially as set forth.

6. In a band-resaw feed-works, a stationary base-frame, a feed-carriage adjustably mounted on the base-frame and having a pair of transverse front and rear table-supports, the rear of which supports is provided in its side next to the saw with a reentrant saw-space, 100 a pair of slide-tables mounted on each of said table-supports, the rear pair of slide-tables carrying two relatively close pairs of upright rotary feed-rolls, and the front pair of slide-tables carrying a single pair of upright feed-rolls arranged in line with the other rolls, and suitable adjusting mechanism for 105 moving the slide-tables of each pair toward and away from the longitudinal saw-line of the works, substantially as set forth. 110

7. In a band-resaw feed-works, a stationary base-frame, a feed-carriage slidably mounted on the base-frame and provided in its side next to the saw with a reentrant saw-space to receive therein the saw, pairs of upright 115 feed-rolls suitably mounted on the carriage respectively at opposite sides of the reentrant saw-space, adjusting mechanism for said rolls, and a longitudinally-arranged rest-bar secured on top of the carriage in line with the longitudinal center of the works below the plane of the lower ends of the feed-rolls and provided at its rear end with a fork or bifurcation to permit the saw to extend in between the front pair of rolls, substantially as set 120 forth. 125

8. In a band-resaw feed-works, a stationary base-frame, a feed-carriage mounted on the base-frame and having a pair of transverse front and rear semitubular table-supports, a 130 pair of slide-tables mounted on each of the table-supports over their open sides and carrying pendent bearing-boxes disposed within the table-supports, upright feed-rolls mount-

- ed on the upright table-supports respectively at opposite sides of the saw-line and carrying on their lower spindle extremities within the table-supports horizontally-disposed beveled 5 gear-wheels, shafts arranged longitudinally within the front and rear table-supports and carrying on their outer ends, beyond the ends of said supports, sprocket-wheels, vertically-disposed beveled gear-wheels slidably mounted 10 or feathered on the shafts in the table-supports and provided with hub extensions journaled in the bearing-boxes at the under sides of the slide-tables, said vertically-disposed beveled gear-wheels meshing with those at 15 the lower spindle ends of the feed-rolls, adjusting mechanism for sliding the tables on said supports, and chain connections between the sprocket-wheels of the oppositely-located shafts, substantially as set forth.
- 20 9. In a band-resaw feed-works, a stationary base-frame, a feed-carriage slidably mounted on the base-frame and having a pair of transverse front and rear semitubular table-supports, a pair of slide-tables mounted on each 25 of the table-supports and carrying rotary upright feed-rolls, shafts arranged longitudinally in the semitubular table-supports and geared with the lower ends of the feed-rolls, said shafts carrying at their outer ends, beyond 30 the ends of the supports, sprocket-wheels, chain connections between the sprocket-wheels of the oppositely-located shafts, wheel-brackets arranged between the table-supports near the ends thereof, vertically-adjustable journal-bolts fitted to said wheel-brackets, and tightener sprocket-wheels journaled on said bolts, substantially as set forth.
- 35 10. In a band-resaw feed-works, a stationary base-frame, a feed-carriage mounted on 40 the base-frame and having a pair of transverse front and rear table-supports, a pair of slide-tables mounted on each of said table-supports and provided with upright roll-brackets, a pair of upright front feed-rolls 45 mounted in the brackets of the front pair of slide-tables, a pair of relatively close rear and intermediate upright feed-rolls mounted in the roll-brackets of the rear pair of the slide-tables, the rear pair of rolls being adapted to 50 receive the saw therebetween and said intermediate rolls being of a smaller diameter than the adjacent rear rolls, gearing connections with the lower ends of the feed-rolls of the front and rear pairs, cog-gearing between the 55 upper spindle extremities of the feed-rolls of the rear and intermediate pairs, and suitable pressure-adjusting mechanism for moving the slide-tables toward and away from the saw-line of the works, substantially as set forth.
- 60 11. In a band-resaw feed-works, a stationary base-frame, a feed-carriage mounted on the base-frame, front and rear pairs of upright feed-rolls movably supported on the carriage respectively at opposite sides of the 65 saw-line, a pair of intermediate upright feed-rolls arranged between and in line with the other pairs of feed-rolls and in a relatively

close relation to the rear feed-rolls and the cutting-point of the saw, adjusting devices for individually adjusting the feed-rolls of 70 the intermediate and front pairs at an inclination to a vertical plane and independently of the rear rolls, and pressure-adjusting mechanism for moving the rolls toward the saw-line, substantially as set forth. 75

12. In a band-resaw feed-works, the combination of a table-support, a pair of slide-tables mounted on said support respectively at opposite sides of the saw-line and provided with upright roll-brackets having at their upper ends horizontally-disposed squared guide-yokes at the outer sides of which yokes are formed integral hollow offstanding bosses provided with threaded openings, squared bearing-boxes slidably mounted in said yokes, 85 bolts connected at their inner ends with said boxes and provided with spaced collars and nuts respectively located within and exterior to said bosses, exteriorly-threaded adjusting-sleeve loosely mounted on the bolts between 90 their collars and nuts and engaging in the openings of the bosses, pivotal bearing-collars pivotally mounted on the slide-tables below the adjustable bearing-boxes, upright rotary feed-rolls having their spindle extremities respectively mounted in the bearing-boxes and pivotal bearing-collars, suitable gearing for turning said rolls, and adjusting mechanism for sliding the tables on their supports, substantially as set forth. 100

13. In a band-resaw feed-works, the combination of a table-support, a pair of slide-tables mounted on said support respectively at opposite sides of the saw-line and carrying upright feed-rolls, a pair of adjusting-105 rods having screw connections at their inner ends respectively with the separate slide-tables and extending beyond one end of the table-support, an equalizing gear connection between the two rods, a vertical rock-shaft 110 supported between the outer ends of the rods, an oscillatory adjusting-lever fitted on the upper end of the rock-shaft and provided with forked ends, knuckle-blocks fitted on the rods and pivotally embraced by the forked 115 ends of said adjusting-lever, a pair of adjusting hand-wheels threaded on one of the rods respectively at opposite sides of the knuckle-block thereon, a single hand-wheel threaded on the other rod at one side of the knuckle-block thereon, a rock-arm fitted at one end on the lower end of the vertical rock-shaft, and a weighted bell-crank lever pivotally supported at its angle and having one of its arms slotted to loosely receive the free end of said 120 rock-arm, substantially as set forth. 125

In testimony that I claim the foregoing as my own I have hereto affixed my signature in the presence of two witnesses.

FRANK McDONOUGH.

Witnesses:

FRANK H. BROWN,
A. J. KEITH.
